UNITED STATES PATENT OFFICE

114,500

DESIGN FOR A TEXTILE FABRIC OR SIMILAR ARTICLE

Louise H. Brewster, Belfast, Maine, assignor to Joseph W. Woods Company, Inc., New York, N. Y., a corporation of New York

Application December 10, 1938, Serial No. 81,700

Term of patent 3½ years

To all whom it may concern:

Be it known that I, Louise H. Brewster, a citizen of the United States of America and a resident of the town of Belfast, county of Waldo, and State of Maine, have invented a new, original, and ornamental Design for a Textile Fabric or Similar Article, of which the following is a specification, reference being had to the accompanying drawing, forming part thereof,

The figure of the drawing is a face view of a textile fabric showing my design, the unit of which is contained within the dot and dash lines shown on the drawing, which unit is continued in regular succession beyond the unit boundary.

I claim:

The ornamental design for a textile fabric or similar article, as described and shown.

LOUISE H. BREWSTER.
